United States Patent Office

Des. 192,948
Patented May 29, 1962

192,948

WATER-CRAFT

Salvatore J. Magri, 4 Carlson Court, East Norwalk, Conn.

Filed Jan. 24, 1961, Ser. No. 63,677

Term of patent 14 years

(Cl. D71—1)

FIG. 1

FIG. 2

FIG. 3

FIG. 4

FIG. 5

The dominant features of my design reside in the portions shown in full lines.

I claim:

The ornamental design for a water-craft, substantially as shown and described.
